UNITED STATES PATENT OFFICE.

EUSEBE LEGER, OF WATERVILLE, MAINE.

PAPER-CUTTER.

SPECIFICATION forming part of Letters Patent No. 225,990, dated March 30, 1880.

Application filed September 24, 1878.

To all whom it may concern:

Be it known that I, EUSEBE LEGER, of Waterville, in the county of Kennebec and State of Maine, have invented certain new and useful Improvements in Paper and Tobacco Cutting Machines; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a side view, partly in section, 15 through $x x$. Fig. 2 is an elevation looking at the end containing the handle.

My invention relates to paper and tobacco cutting machines, and is intended to be used as a paper-cutter for printers, book-binders, &c., and also, being reduced to the proper size, 20 as a tobacco-cutter for the cutting of plug-tobacco, herbs, &c.

It consists in the application of well-known mechanical principles in new combination and 25 in compact and durable form to the cutting of paper and tobacco.

In the accompanying drawings, C and B are two elbow-levers, hung by trunnions at D and D' to the bed of the machine I, the lever C being 30 elongated into the arm or handle H. To these levers, at the points a and a' , are hung the ends of a knife, A, and at the points b and b' are hung the ends of the bar E.

It is evident that when the handle H of the 35 lever C is drawn back, as indicated by the dotted lines, the knife, following the points a and a' , will be drawn downward and backward to the bed I of the machine with a diagonal motion, which is so essential in the cutting of 40 paper and kindred substances.

Leaving out of account the action of the bar E, it is evident that when the edge of the knife comes near the bed the end which is at B will have a much less downward force than the end at C, for as a' moves downward it approaches to a point in the line of D' and a , as is shown by their dotted positions, and these three points thus approximate to the condition of dead-centers, resulting in great loss of power in the lever B. At this point, however, the 45 bar or rod E has arrived at a position where b' is vertically above D', so that the full effect of the force applied at H is transmitted to a' through the bar E, acting on the point b' . Thus throughout the whole stroke the force 50 at the end of each knife A is equalized by the action of the bar E, while without this bar the machine would be inefficient at the latter end of the stroke, as found by experience.

In securing the knife in the manner above 55 described to the levers B and C said levers act as guides to hold the knife steadily in place, thus dispensing with the guides used in some similar machines.

Having thus described my invention, what 60 I claim as new, and desire to secure by Letters Patent, is—

In a paper or tobacco cutter, the elbow-levers B and C, hung on trunnions D and D' to machine-bed I, and having knife A, hung to 65 them at a a' , combined with bar E and handle H, substantially as and for the purposes set forth.

In testimony that I claim the foregoing as my own I affix my signature in presence of 70 two witnesses.

EUSEBE LEGER.
